CLAIM

The ornamental design for a gaming table as shown and described.

DESCRIPTION

FIG. 1 is an upper perspective view.

FIG. 2 is a lower perspective view.

FIG. 3 is a top plan view.

FIG. 4 is a bottom plan view.

FIG. 5 is a front side elevation view, the rear view being a mirror image thereof.

FIG. 6 is a right side elevation view, the left side being a mirror image thereof.

FIG. 7 is a front side cross-section elevation view taken at 7-7 in FIG. 3; and,

FIG. 8 is a front side cross-section elevation view taken at 8-8 in FIG. 3.

The broken lines immediately adjacent to the shaded areas depict the bounds of the claimed design, while all other broken lines are directed to environment. The broken lines form no part of the claimed designs.

1 Claim, 5 Drawing Sheets
